UNITED STATES PATENT OFFICE.

BAYARD E. TAYLOR, OF OAK PARK, ILLINOIS.

LOCK FOR DOORS AND WINDOWS.

1,246,350.

Specification of Letters Patent. Patented Nov. 13, 1917.

Application filed September 10, 1915. Serial No. 49,975.

To all whom it may concern:

Be it known that I, BAYARD E. TAYLOR, a citizen of the United States, and a resident of the town of Oak Park, in the county of Cook and State of Illinois, have invented certain new and useful Improvements in Locks for Doors or Windows; and I do hereby declare that the following is a full, clear, and exact description of the same, reference being had to the accompanying drawings, and to the numerals of reference marked thereon, which form a part of this specification.

This invention relates to a type of lock wherein a latch member is connected on the hinge side of a casing or frame for a door or window and has sliding relation with a casing mounted upon the door or window to latch when the door or window is swung from open to closed position. Furthermore, when the mechanisms are interlocked or latched as the door is swung to closed position, said mechanisms are further actuatable to draw the door or window tightly closed in its frame by exerting stress upon the mechanisms and moving the same beyond dead center position to prevent accidental release thereof.

It is an object therefore of this invention to construct an improved type of lock wherein a latch member is mounted on the hinge side of a frame or casing and acts automatically to latch with mechanisms mounted on the door or window when the same is swung into closed position, and with said mechanisms actuatable by a suitable handle for the purpose to tension said latch member to draw the door tightly closed, and also actuatable to positively release said mechanisms from the latch member to permit opening of the door.

It is also an object of this invention to construct a locking device comprising a slidable latch member adapted to interlock with an adjustable mechanism acting, when adjusted in one direction, to tension the latch member and said mechanism to hold the two tightly interlocked with one another, and, when actuated in the opposite direction serving to positively disengage the same into release position, with resilient means forming a part of the mechanism acting normally to return the parts to normal position, with the latch and mechanism loosely interlocked with one another or with the mechanism disposed in a position to re-

ceive the latch interlocking automatically therewith.

It is also an object of this invention to construct a locking device adjustable at the hinge side of a door and its frame comprising means rigidly secured on the frame, and having telescoping engagement with mechanisms secured upon the door, and with said means and mechanisms acting automatically to interlock or latch with one another when the door is swung from open to closed position and capable of further actuation to stress said means and mechanisms to draw the door tightly closed in the frame.

It is furthermore an important object of this invention to construct an adjustable lock adapted for connection on the inside of a door or window, so constructed as to insure positive alinement of the parts irrespective of sagging of the door in its frame, acting automatically to latch when the door is swung into closed position, and capable of actuation to draw the door tightly closed in its frame after the same has been swung into closed position.

It is finally an object of this invention to construct an improved type of lock, simple in construction and operation, and cheap to manufacture.

The invention (in a preferred form) is illustrated in the drawings and hereinafter more fully described.

On the drawings:

Figure 1 is a fragmentary top plan view of a door hinged in its frame and equipped with a lock embodying the principles of my invention, and showing an open position of adjustment of the door in dotted lines.

Fig. 2 is an interior rear view of the mechanisms with parts shown in section and parts in elevation.

Fig. 3 is a similar interior front view of the mechanisms.

Fig. 4 is a detail section taken on line 4-4 of Fig. 2.

Fig. 5 is a section taken on line 5-5 of Fig. 2.

Fig. 6 is a view similar to Fig. 2, but showing the parts in locking position.

Fig. 7 is a view similar to Fig. 4, but showing the parts in locking position.

Fig. 8 is a view similar to Fig. 7, showing the parts in release position.

Fig. 9 is a section taken on line 9-9 of Fig. 3.

Fig. 10 is a section taken on line 10—10 of Fig. 8, with parts shown in elevation.

Fig. 11 is an end view of the mechanism.

Fig. 12 is a detail section illustrating the locking clamping means on the telescoping members of the device.

As shown in the drawings:

The reference numeral 1, indicates as a whole a door mounted in a frame 2, and connected thereto by means of hinges 3. A channel shaped casing is provided, denoted by the reference numeral 4, having lateral attaching flanges 5, integral therewith, and with a cover plate 6, adapted to be connected to said attaching flanges when the casing and cover plate are mounted upon the door by means of screws extending through holes or apertures 7. Secured at one end of the casing 4, are a pair of arms 8, affording a yoke for attachment therein of a tubular member 9, by means of a pintle 10. Slidably mounted within said tubular member 9, is a long rod 11, which, at its inner end within said tubular member 9, has adjustably threaded thereinto a latch member 12, extending slidably through a guiding or alining collar 12^a, and at its other end said rod 11, is connected by means of a pintle 13, to a hinge bracket 14, secured upon the frame 2. At the outer end of the tubular member 9, a collar 15, is threaded thereon, the detail of which is shown in Fig. 12, and threaded through a boss formed therein, is a clamping screw 16, having an actuating head 17, whereby said screw may be threaded inwardly to clamp tightly against the inner telescoping rod 11, to prevent movement thereof in the tubular telescoping member 9.

Slidably mounted within said casing 4, against the cover plate 6, thereof, is a T-shaped slide plate 18, having at its inner end a long tongue extension 19, and with beveled abutments 20, formed on each side of said tongue extension. Slidably mounted above said plate 18, is a long tilting latch plate 21, at its rear end having a rectangular slot 22, the rear end of which is beveled adapted for engagement with the forward end of the latch member 12, and at its other provided with an enlarged curved recess 23, within which is rotatably mounted an eccentric 24, secured upon an actuating handle 25, which is journaled transversely through the casing 4, and the cover plate 6.

Formed on the outer surface of said plate 21, at the side thereof, are a pair of inclined abutments 26, adapted for coaction with the beveled portions 20, of said slide plate 18, to slide thereon and cause tilting of the plate 21. A leaf spring 27, is secured on the inner surface of the wall of the casing 4, and bears outwardly against the rear surface of the plate 21, to close the same normally flat against the plate 18, and parallel to the

walls of the casing to resist tilting thereof. Slidably mounted on the forward end of the plate 21, is a U-shaped or forked plate 28, and formed thereon are outwardly turned abutments 29, disposed on each side of the plate 21. Likewise formed integrally on the plate 21, are outwardly turned abutments 30, and disposed between said respective pairs of abutments 29 and 30, are coiled compression springs 31. Mounted between the forked extensions of the plate 28, is a crank 32, rigidly secured or formed on the handle 25, and when the handle is rotated, acting to thrust said forked plate 28, rearwardly in the casing thus compressing said springs 31. Another crank 33, is also formed on the handle 25, disposed adjacent the cover plate 6, adapted to actuate the slide plate 18, which, due to the fact that the head or extension thereof contacts the abutments 29, of said plate 28, acts to compress the springs 31, to resist movement of the handle.

The operation is as follows:

The parts as shown in illustration in Figs. 2, 3, 4, and 5, are in normal or neutral position, that is, with the latch member 12, loosely engaged with the tiltable slide plate 21. When it is desired to lock the door closed in its frame, the handle 25, is rotated clockwise or to the right referring to the front view of the device shown in Fig. 3, whereby the eccentric 24, acts to thrust the slide plate 21, forwardly so that the beveled edge of the slot 22, therein, is drawn against the beveled hooked end of the latch 12, and as said eccentric 24, is rotated past the dead center position, a tension is exerted upon the parts of the mechanism to hold the same tightly engaged with one another and with the door, of course, drawn tightly closed in the frame. Furthermore, the crank 33, thrusts the plate 18, rearwardly and with it the plate 28, thereby compressing the springs 31, which, when the lock is released, aid in returning the parts to normal or neutral position. When a releasing movement takes place, the handle, of course, first passes into neutral position whereupon the parts assume the position shown in Figs. 2 to 5, inclusive, and with a continued reverse rotation of the handle, that is, counter-clockwise or to the left referring to the front view of the device shown in Fig. 3, the respective cranks 32 and 33, on said handle act to thrust the respective plates 18 and 28, rearwardly within the casing, the plate 28 acting to compress the springs 31, thus resisting the movement of the handle.

On the other hand, rearward movement of the plate 18, causes the beveled edges or portions 20, thereof, to engage beneath the abutments 26, on said tilting lever 21, thereby tilting the same into the position shown in Fig. 8, and lifting the slot 22, entirely away from the end of the latch member 12, so that

when the door is swung open, said latch member may be withdrawn from the casing 4, as said elements 9 and 11, are drawn apart, and with the latch 12, of course, being drawn inwardly into the tubular member 9. Of course, release of the handle 25, after the door has been swung partly open so as to throw the latch 12, out of possible engagement with the slot 22, permits the parts to return to normal under the stress of the leaf spring 27, which throws said plate 21, outwardly into parallel relation with the casing, and, of course, the springs 31, act to return the handle to upright or neutral position.

If the door is swung into closed position, the latch 12, is projected into the rear end of the casing 4, elevating the end of the plate 21, against the stress of the leaf spring 27, and latching in the slot 22, whereupon the handle is rotated in a direction to draw the plate 21, tightly into engagement with the end of said latch member to draw the door tightly closed and to maintain the same locked in the frame. It is thus apparent that the springs 31, are compressed whenever the handle is rotated from neutral position either into release or into locking position, due to the fact that said plate 28, is struck rearwardly when the handle is thrown into locking position by the plate 18, to cause compression of the springs, and when the handle is thrown toward release position the plate 28, is thrust rearwardly by the crank 32.

If it is desired to lock the door in an open position of adjustment as, for instance, an automobile door for ventilating purposes, the door is moved into an open position and the screw 16, threaded inwardly by means of the head 17, thus clamping the rod 11, within the tubular member 9, and preventing relative movement thereof, the door being thereby held in a rigid position. Said clamping mechanism may also be used as an auxiliary lock when the door is moved into locked closed position if so desired.

I am aware that various details of construction may be varied through a wide range without departing from the principles of this invention and I therefore do not purpose limiting the patent granted otherwise than necessitated by the scope of the claims.

I claim as my invention:

55 1. In a door lock of the class described the combination with a door and its casing, of means secured on the casing and mechanism secured upon the door, a telescoping connection between said means and mechanism, and a rigid latch member forming a part of said telescoping connection adapted to positively interlock with said mechanism to hold the door locked closed.

2. In a device of the class described the combination with a door and its frame, of

a casing mounted on the door, locking mechanisms within said casing, a telescoping connection between said casing and the frame of the door, and a rigid latch member forming a part of said telescoping connection 70 and adapted to extend into the casing to interlock with the mechanisms therein to lock the door closed.

3. In a device of the class described the combination with a door and its frame, of 75 a casing mounted on the door, a telescopic connection between the casing and the frame, locking mechanisms within said casing, a latch member forming a part of said telescopic connection adapted to extend 80 into the casing to interlock with said mechanisms, and means actuating said mechanisms to draw the same tightly into engagement with said latch member to draw the door tightly closed into locked position. 85

4. In a device of the class described the combination with a door and its frame, of a casing mounted on the door, a telescopic connection between said casing and the frame, a rigid latch member forming a part 90 of said telescopic connection adapted to slide within said casing, locking mechanism within said casing comprising a tilttable slideable plate adapted to engage said latch, a spring to resist movement of said plate, and 95 eccentric means for actuating the same to draw the same tightly into engagement with said latch to draw the door tightly closed in locked position.

5. The combination of a door and its 100 frame, of a casing mounted upon the door, a telescopic connection between said frame and said casing, a rigid latch member forming a part of said telescopic connection extending slidably into said casing, locking 105 mechanisms within said casing comprising a tilttable slideable plate, an eccentric for drawing said plate into tight engagement with said latch member to lock the door tightly closed, and means associated with 110 said eccentric adapted to tilt said plate out of engagement with the latch to permit release thereof and movement of the door into open position.

6. In a device of the class described the 115 combination with a door and its frame, of means secured upon the frame and mechanism secured upon the door and connections therebetween, locking devices within said mechanism and a rigid latch member 120 forming a part of said means adapted to coact with said mechanism to draw the door tightly closed into locked position.

7. In a device of the class described the combination with a door and its frame, of 125 telescopic means connected with said door and frame, and hooked means therein adapted to draw the door tightly closed into locked position.

8. In a device of the class described the 130

combination with a door and its frame, of spring controlled eccentric locking means associated therewith, and means projecting therein to draw the door tightly closed into 5 locked position.

9. The combination of a door and its frame, of locking means mounted on said door, and telescopic means connected to said sash co-acting with said locking means to 10 draw the door into closed locked position.

10. The combination of a door and its sash, of spring controlled eccentric locking means mounted on said door, telescopic means connected to said sash and co-acting 15 with said locking means to draw the door into a closed locked position, and mechanism associated with said telescopic means adapted to hold said door in an adjusted open position.

20. 11. In a device of the class described the combination with a door and its frame, of

locking mechanism mounted on said door, and adjustable telescopic means connected with said sash and co-acting with said locking mechanism for locking said door in 25 closed position or holding the same in an adjusted open position.

12. In a device of the class described the combination with a door and its frame, of locking means on said door, an adjustable 30 telescopic locking mechanism connected with said frame, and means thereon co-acting with said locking means to draw the door into locked position or hold the same in an adjusted open position. 35

In testimony whereof I have hereunto subscribed my name in the presence of two subscribing witnesses.
